US0D1101584S

(12) **United States Design Patent** (10) **Patent No.:** **US D1,101,584 S**
(45) **Date of Patent:** **** Nov. 11, 2025**

(54) **PERSONAL TESTER**

(71) Applicant: **Consumer Safety Technology, LLC**,
Des Moines, IA (US)

(72) Inventors: **Christopher D. Justice**, Leawood, KS
(US); **Zouhair Talbi**, Prairie Village,
KS (US); **Stephen R. Nyberg**, Kansas
City, MO (US); **Erika F. Lobo**, Prairie
Village, KS (US); **Nathan S. Asinger**,
Overland Park, KS (US); **Joel M.
Murphy**, Kansas City, MO (US)

(73) Assignee: **Consumer Safety Technology, LLC**,
Des Moines, IA (US)

(**) Term: **15 Years**

(21) Appl. No.: **29/898,588**

(22) Filed: **Jul. 28, 2023**

(51) LOC (15) Cl. **24-02**

(52) U.S. Cl.

USPC **D24/164**; D10/78; D10/81

(57) **CLAIM**

The ornamental design for a personal tester, as shown and described.

DESCRIPTION

FIG. 1 is a top front right side perspective view of a personal tester.

FIG. 2 is a front view of the personal tester of FIG. 1.

FIG. 3 is a rear view of the personal tester of FIG. 1.

FIG. 4 is a right side view of the personal tester of FIG. 1.

FIG. 5 is a left side view of the personal tester of FIG. 1.

FIG. 6 is a top view of the personal tester of FIG. 1; and,

FIG. 7 is a bottom view of the personal tester of FIG. 1.

The broken lines in the drawings illustrate portions of the personal tester that form no part of the claim.

1 Claim, 7 Drawing Sheets
